(57) CLAIM

The ornamental design for a bottle cap as shown and described.

DESCRIPTION

FIG. 1 is a front perspective view of a bottle cap showing my design;

FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a bottom plan view thereof.

The broken lines in the figures are shown for the purpose of illustrating both parts of the bottle cap as well as environmental subject matter of an exemplary bottle. None of the broken lines form part of the claimed design.
